UNITED STATES PATENT OFFICE.

HENRY G. VOIGHT AND NORMAN B. HURD, OF NEW BRITAIN, CONNECTICUT, ASSIGNORS TO RUSSELL & ERWIN MANUFACTURING COMPANY, OF NEW BRITAIN, CONNECTICUT, A CORPORATION OF CONNECTICUT.

LOCK.

1,024,467.

Specification of Letters Patent. Patented Apr. 23, 1912.

Application filed October 26, 1911. Serial No. 656,843.

To all whom it may concern:

Be it known that we, HENRY G. VOIGHT and NORMAN B. HURD, citizens of the United States, residing at New Britain, 5 county of Hartford, State of Connecticut, have invented certain new and useful Improvements in Locks, of which the following is a full, clear, and exact description.

Our invention relates to improvements in 10 locks, and is particularly concerned with a lock specially adapted for use on the door of a private bathroom communicating with a hotel apartment.

The object of the invention is to provide 15 means whereby the bathroom door may be locked from the inside against unlocking by the maid's or housekeeper's key, but at the same time in case of emergency the door may be unlocked by the use of a 20 guard key usually retained at the office of the hotel, or by a so-called emergency key in the hands of the proprietor of the hotel.

A further object is to provide means 25 whereby the door may be locked by the holder of the guard or emergency key so that it cannot be unlocked from the apartment side by any except the guard or emergency keys, whereby the bathroom may be closed against use when the apartment 30 is rented without the bath.

A further object is to provide means 35 whereby the door may be unlocked from the inner or bathroom side at all times, notwithstanding it may have been locked from the apartment side by any of the keys adapted to the lock.

With these objects in view, the invention 40 consists in the construction and arrangement of parts, a preferred embodiment of which is illustrated in the accompanying drawings, in which—

Figure 1 is a side elevation of the lock complete, the cover plate being removed for clear illustration. Fig. 2 is a view similar to Fig. 1, certain of the locking tumblers being removed for clear illustration. Fig. 3 is a side elevation of an emergency tumbler used in the lock. Fig. 4 is a side elevation of a tumbler bar for connecting the 45 two sets of tumblers of the lock. Fig. 5 is a side elevation of a companion tumbler bar. Fig. 6 is a view of a tumbler or tumbler lever included in one of the sets of

tumblers. Fig. 7 comprises a side and edge view of another tumbler lever. Fig. 8 is a 55 view of the dead bolt detached. Fig. 9 is a view of a thumb-turn roll-back used in the lock. Fig. 10 is a fragmentary view of the cover plate showing the key hole therein. Figs. 11, 12, 13, 14 and 15 comprise fragmentary views of the bitting of the guest, maid's, housekeeper's, guard and emergency 60 keys.

In the embodiment of our invention herein selected for illustration, 1 indicates the lock case, 2 the face plate, 3 the ordinary latch bolt used in locks of this character and adapted to be operated by a roll-back 4.

5 indicates the dead bolt slidably mounted 70 ed on a stud 6 on the lock case.

7 is a stud on the lock case, upon which the upper set of tumblers which coöperate with the racking stump 8 of the dead bolt are mounted. These tumblers comprise several of the ordinary gated tumblers 9, and included in this set of tumblers is a so-called emergency tumbler 10, such as illustrated in Fig. 2, having an emergency tongue 11, which coöperates with the racking stump 8 in the manner hereinafter described. Upon a second stud 12 is mounted a second set of tumblers, one of which, 13, is provided with an end projection 14, which engages a notch 15 in a tumbler 85 connecting bar 16, see Fig. 4. The emergency tumbler 10 lies below one or more of the gated tumblers, and has a projection 17, which alines with a slot 16' in the tumbler connecting bar 16, so that when this 90 tumbler bar only is actuated, as hereinafter described, the emergency tumbler 10 is not raised. Below the lower set of tumblers is a thumb-turn roll-back 18 having a thumb-turn (not shown) extending to the inner 95 or bathroom side of the door only. This thumb-turn, as will be seen from an inspection of Figs. 1 and 9, always operates the tumbler 13, and consequently, through the tumbler bar 16, likewise operates the gated 100 tumblers of the upper set, each of which is provided with an extension such as 9' adapted to be engaged by the upper end of the tumbler bar 16. Hence, when the thumb-turn is turned from the inside, it 105 serves to release the tumblers of the upper

set from the racking stump 8, thus permitting projection and retraction of the dead bolt 5.

It is desirable, when the bathroom is occupied, that entrance thereto be barred against the holders of the maid's or housekeeper's keys. To this end there is included in the lower set of tumblers a tumbler 19, Fig. 7, which is pivoted upon a stud 20 on the lock case, said stud projecting through a slot 21 on the dead bolt, so that the latter is free to move forward or back. The tumbler 19 is provided at one side of the pivot 20 with a stud 22, which extends through slots such as 23 in several of the tumblers, such as 24, of the lower set. The rear end of the tumbler 19 is provided with a projection 25, which extends into a notch 26, Fig. 5, of a companion tumbler bar 27. This tumbler bar is provided with a cut-away portion 28, which allows free play of the projection 14 of the tumbler 13, whereby the latter tumbler does not operate the second tumbler bar 27. The upper end 27' of the tumbler bar 27 is solid, and thereby engages the projections 9' of all of the gated tumblers of the upper set and also the shoulder 17 of the emergency tumbler. The tumblers such as 24 of the lower set, are normally held by their springs 24' in the position indicated in Figs. 1 and 2, wherein the stud 22 of the tumbler 19 lies in the upper ends of the slots such as 23 in said tumblers 24, so that when said tumblers 24 are depressed, as hereinafter described, the tumbler lever 19 is tilted and thus raises the tumbler bar 27, which in turn raises the gated tumblers of the upper set to free the racking stump 8 therefrom, and also raises the emergency tumbler.

The cover or outside plate of the lock is provided with a double-ended key-hole 29, Fig. 10, and opposite the upper end of said key-hole is a key post 30, while opposite the lower end of said key-hole is a key pin-receiving aperture 31 in the back plate of the lock. The guest, guard and emergency keys are of the drill pin type, and may be inserted in the key-hole 29 in normal position, taking over the key post 30, while the maid's and housekeeper's keys are of the solid pin type and are adapted to be inserted in the key-hole 29 in inverted position, the solid pins having a bearing in the pin aperture 31. The guard and emergency keys operate directly upon the upper set of tumblers in projecting and retracting the dead bolt, whereas the maid's and housekeeper's keys operate on the tumblers 24 of the lower set, and consequently, through the tumblers 19 and tumbler bar 27, indirectly operate the tumblers of the upper set. Furthermore, the guard and emergency keys are so bitted that they do not raise the emergency tumbler 10 when projecting the dead bolt, so that when

the dead bolt is projected by them the emergency tongue 11 of the emergency tumbler lies below the racking stump 8. When, on the other hand, the upper set of tumblers are operated by the tumbler bar 27 through the agency of the tumbler 19 when actuated by the maid's or housekeeper's keys, the emergency tumbler is raised so that the racking stump 8 takes a position below the emergency tongue 11, as indicated in Fig. 2. Hence when the dead bolt is projected by the guard or emergency keys, it cannot be retracted by the maid's or housekeeper's keys, since these keys are blocked by the position of the emergency tongue relative to the racking stump.

The thumb-turn roll-back 18 is provided with notches 32, Fig. 9, which are alined with the tumbler 19 of the lower set. The upper roll-back arms of this roll-back, however, are arranged to engage the tumbler 13, hence when the thumb-turn roll-back is operated to project the latch bolt, it simultaneously operates the tumbler 13 and thereby the tumbler bar 16, which in turn frees the racking stump 8 from the gated tumblers of the upper set. This tumbler bar 16, by reason of its notch 18, does not raise the emergency tumbler 10, and furthermore, since the roll-back, by reason of its notch 32, does not operate the tumbler 19, the operation of the roll-back in projecting the dead bolt does not raise the emergency tumbler 10, so that the dead bolt so operated cannot be retracted by the maid's or housekeeper's keys, but can be retracted by the guard or emergency key.

From the above described construction it will be seen that, while the bathroom door may be locked by the occupant of the bathroom against the maid's and housekeeper's keys, it may be unlocked from the outside in case of emergency by the guard or emergency key. Furthermore, since the thumb-turn roll-back may only be operated from the inner or bathroom side of the door, the door may be locked by the guard and emergency keys against unlocking by any but the guard and emergency keys; hence the private bathroom cannot be surreptitiously thrown into communication with the apartment by the holders of the maid's or housekeeper's keys. It is understood, moreover, that the guest key to the corridor door lock is incapable of locking or unlocking the bathroom door lock. This may be provided for by locating short studs 33 in the path of the ward of the guest key and so bitting said key that it cannot clear these projections, although the other keys of the series are bitted to clear them.

While we have herein described a preferred embodiment of our invention, it is to be understood that the same may be altered in detail and relative arrangement of

parts without departing from the spirit or scope of the appended claims.

What we claim is:

1. In a lock, the combination with a casing, of a dead bolt, two sets of tumblers therefor, one of said sets including an emergency tumbler provided with a part adapted to be so positioned as to block the operation of said dead bolt by certain keys, connecting means for said tumblers, a key-hole at one side only of said casing, a plurality of keys including a maid's, housekeeper's, guard and emergency key, said key-hole being constructed to receive certain of said keys in normal position only to operate directly upon the upper set of tumblers and being constructed to receive other of said keys in inverted position only to operate directly upon the lower set of tumblers, said first mentioned keys operating directly upon said upper set of tumblers being bitted as to so position the emergency tumbler, in projecting the dead bolt, as to block operation of the other keys, said maid's and housekeeper's keys being so bitted as to position the emergency tumbler, in projecting the dead bolt, as to permit retraction thereof by any of the keys, and a thumb-turn on the side of the lock opposite the key-hole provided with means for projecting and retracting the dead bolt and constructed and arranged to position the emergency tumbler, in projecting the dead bolt, to prevent retraction thereof by any except said first mentioned keys.

2. In a lock, the combination with a casing of a dead bolt, two sets of tumblers therefor, connecting means for said sets, a key-hole at one side of said casing only, a plurality of keys including a maid's, housekeeper's, guard and emergency key, said key-hole being constructed to receive certain of said keys to operate only on one set of said tumblers, and the other of said keys to operate only on the other set of tumblers, one of said sets of tumblers including an emergency tumbler provided with a part adapted to be so positioned as to block the operation of said dead bolt by certain keys and adapted to be operated by the first mentioned group of keys to prevent retraction of the bolt by the second group of keys, the second set of tumblers including a tumbler adapted to operate said connecting means to in turn operate said first set of tumblers including the emergency tumbler so that the bolt may be retracted by any of said set of keys, and a thumb-turn arranged to operate upon the second set of tumblers and through said connecting means to operate the first set of tumblers, including the emergency tumbler, so that the dead bolt may be retracted only by certain of said keys.

3. In a lock, the combination with a cas-

ing of a dead bolt, an upper and lower set of tumblers therefor, one of said sets including an emergency tumbler provided with a part adapted to be so positioned as to block the operation of said dead bolt by certain keys, a pair of connecting bars for said tumbler sets, a key-hole at one side only of said casing, a thumb-turn roll-back operable only from the opposite side of said casing, a plurality of keys including a maid's, housekeeper's, guard and emergency key, said key-hole being adapted to receive the guard and emergency keys to operate directly upon the upper set of tumblers and to receive the maid's and housekeeper's keys to operate directly upon the lower set of tumblers, said lower set of tumblers including a tumbler adapted to operate said connecting bar to raise said emergency tumbler in projecting the dead bolt, said guard and emergency keys being so bitted as not to raise the emergency tumbler in projecting the dead bolt whereby the dead bolt is blocked against operation by said maid's and housekeeper's key and may be retracted only by the guard and emergency keys when projected by said keys, said thumb-turn being arranged to project the dead bolt without raising said emergency tumbler whereby said bolt may be retracted only by the said thumb-turn or by said guard or emergency keys when projected by said thumb-turn.

4. In a lock, the combination with a casing of a dead bolt, an upper and lower set of tumblers therefor, one of said sets including an emergency tumbler provided with a part adapted to be so positioned as to block the operation of said dead bolt by certain keys, tumbler connecting bars for said sets, the lower set of tumblers including tumblers each arranged to operate one of said connecting bars, one only of said connecting bars being arranged to raise said emergency tumbler, a plurality of keys including a maid's, housekeeper's, guard and emergency key, one side of said casing only having a key-hole, said key-hole being adapted to receive said guard and emergency keys to operate directly upon the upper set of tumblers and being adapted to receive the maid's and housekeeper's key to operate directly upon the lower set of tumblers, said guard and emergency keys being so bitted as to project the dead bolt without raising the emergency tumbler, said maid's and housekeeper's keys being so bitted as to raise the emergency tumbler through the agency of one of the tumblers of the lower set and one of said connecting bars whereby the bolt is blocked against operation by said maid's and housekeeper's key and may be retracted only by the guard or the emergency key when projected by said keys, and a thumb-turn arranged to operate said lower set of tumblers and thereby one of said con-

necting bars to operate said upper tumblers, with the exception of said emergency tumbler, whereby the bolt may be retracted by the guard or emergency keys from the outside or by the thumb-turn from the inside only, when projected by the thumb-turn from the inside.

5. In a lock, the combination with a casing of a dead bolt, two sets of tumblers therefor, 10 one of said sets including an emergency tumbler provided with a part adapted to be so positioned as to block the operation of said dead bolt by certain keys, a pair of connecting bars for said sets of tumblers, a 15 second set including tumblers each adapted to operate one of said connecting bars, said casing having a key-hole upon one side only and said lock having a thumb-turn roll-back provided with a thumb-turn at the opposite 20 side only of said casing, a plurality of keys including a maid's housekeeper's, guard and emergency key, said key-hole being adapted to receive the maid's and housekeeper's keys in normal position only to operate directly

upon the upper set of tumblers to project 25 the dead bolt without raising the emergency tumbler, said key-hole being adapted to receive the maid's and housekeeper's keys in inverted position only to operate upon the lower set of tumblers directly and to operate 30 the upper set, including the emergency tumbler, through the agency of one of said connecting bars whereby when the dead bolt is projected by the guard and emergency keys it is blocked against retraction by the maid's 35 or housekeeper's keys, said thumb-turn being adapted to operate one only of said connecting bars in projecting the dead bolt to operate the upper set of tumblers, with the exception of the emergency tumbler, 40 whereby the dead bolt may be retracted by the guard or emergency keys or the thumb-turn when projected by said thumb-turn.

Correction in Letters Patent No. 1,024,467.

It is hereby certified that in Letters Patent No. 1,024,467, granted April 23, 1912, upon the application of Henry G. Voight and Norman B. Hurd, of New Britain, Connecticut, for an improvement in "Locks," an error appears in the printed specification requiring correction as follows: Page 4, line 23, for the syllable and words "ceive the maid's and housekeeper's" read *to receive said guard and emergency*; and that the said Letters Patent should be read with this correction therein that the same may conform to the record of the case in the Patent Office.

Signed and sealed this 14th day of May, A. D., 1912.

[SEAL.]

C. C. BILLINGS,

Acting Commissioner of Patents.
